(57) **CLAIM**

I claim the ornamental design for a hose termination bracket, as shown and described.

DESCRIPTIONFIG. 1 is a front perspective view showing my design
FIG. 2 is a front view; the rear view is identical to the front view

FIG. 3 is a left side view; the right side view is identical to the left side view

FIG. 4 is a top view; and,

FIG. 5 is a bottom view.
